Letters Patent No. 964 Dated June 21st 1864

Antedated May 31st 1864

Design for a Lady's Hat

The schedule referred to in these Letters Patent and making part of the same.

To all Persons to whom these Presents shall come:

Be it known that I, William E. George, of Wrentham, in the County of Norfolk and State of Massachusetts, have invented or produced a new and ornamental Design for a Lady's Hat, and I do hereby declare the same to be fully described in the following specification, and represented in the accompanying drawings, of which

Figure 1 denotes a top view, Figure 2 a side elevation, Figure 3 a longitudinal section, and Figure 4 a transverse section of a Hat containing my design.

In carrying out the design, the body *a* of the hat is to be of an oval form to fit one person's head, the crown *b* being somewhat convex, the rim *c*, also of an oval form, is arranged eccentrically with respect to the body and is concave convex, as shown in the drawings. There is at the outer edge of the rim *c* an ornamental quilling *d*, formed by bending a band in a series of triangles and parallelograms, the triangles appearing on one side, and the parallelograms on the other side of the quilling. One half of the triangles come before the other half of them, and besides each of the triangles is arranged so as to lap on the two which may be either next above or next below the same being as shown in figure 5, in which *e*, *e*, and *f*, *f* denote the two series of triangles and their arrangement. Figure 6 represents

OCT. 1964

the underside of the quilling or braid which has the form of a series of parallel
logograms, g.g., each of which makes a right angle with the other, mesch. a.t.
I claim as my invention the above described design for a lady's hat.
